UNITED STATES PATENT OFFICE.

EUGENE GRANSAULL, OF NEW YORK, N. Y.

TELEPHONE ATTACHMENT.

1,084,328.

Specification of Letters Patent.

Patented Jan. 13, 1914.

Application filed November 27, 1912. Serial No. 733,770.

To all whom it may concern:

Be it known that I, EUGENE GRANSAULL, a subject of Great Britain, residing at New York, in the county of New York and State of New York, have invented new and useful Telephone Attachments, of which the following is a specification.

My invention relates to improvements in telephone-attachments in which a sound-amplifier is attached to the receiver of the telephone and in which a bracket, equipped with a hook engaging the receiver to hold it in an upright position and with a flattened disk in the nature of a cam, rotated by a projecting pin, is attached to the telephone, adjacent to the switch-hook thereof. This bracket is attached to the telephone in such manner that when the pin on which the cam rotates is turned, the receiver rack or switch-hook of the telephone is lifted and lowered and the telephonic connection so made and broken.

The objects of my improvements are, first, to provide improved means for making and breaking telephonic connections without removing the receiver from its rack or from the switch-hook of telephone; second, to provide improved means of saving time in the use of telephones; third to provide improved means of using the telephone in such manner that the person using it need not employ his hand or hands for the purpose after the connection is made; but may have both hands entirely free during the conversations while waiting to begin conversations and while waiting to resume interrupted conversations; fourth, to provide improved means of bringing and keeping in juxtaposition to the ear of the speaker when he is in the act of talking into the transmitter of the telephone, the trumpet end of the sound-amplifier attached to the receiver, without requiring the use of either of his hands for the purpose; fifth, to provide means for amplifying the acoustic effects of the receiver; and to provide other improvements that will appear in the specification and claims below. I attain these objects by the devices illustrated in the accompanying drawings in which—

Figure 1 is a side elevation partly in section, showing part of my attachment, namely the sound-amplifier mounted on a desk telephone and ready for use, and a front view of the receiver holder in use. Fig. 2 is a side elevation showing part of my attachment on a telephone, comprising a bracket

affixed adjacent to the switch-hook of the telephone, equipped with a cam and a holder for the receiver; as well as the part of the sound-amplifier attached at the mouth of the receiver. Fig. 3 is a cross section on line 3—3 of Fig. 2 looking down. Fig. 4 is a detail of the bracket showing the cam and the pin by which it is rotated. Fig. 5 is a front elevation of the bracket comprising the cam, flat strips and the holder for the telephone receiver. Fig. 6 is a front elevation showing my attachments mounted on a desk telephone and ready for use, and showing the sound-amplifier attached to the receiver when it is in its normal position of rest on the switch-hook, instead of being inverted as in Fig. 1.

Figs. 1 to 5 of the drawings show one form of my invention comprising a sound-amplifier, 1, attached by its cup-shaped end, 2, to the mouth of the receiver 3; a bracket, attached adjacent to the switch-hook of the telephone and consisting of a collar, 4, a cam, 5, flat strips 6 and 7, a pin, 8 by which the cam 5 is rotated and a holder for the receiver, 9, attached rigidly to the flat strips 6 and 7.

The sound-amplifier is attached at its cup-shaped end 2, to the mouth of the receiver 3 and held rigid against the outer rim 12 of the mouth of the receiver, by the screws 10 and 11 of which there is a plurality, passing through the rim of the cup-shaped end 2 of the sound-amplifier. Attached to this cup-shaped end, 2, of the amplifier 1, is its tubular part 13, communicating with the cup-shaped end 2 and through it with the receiver, 3, without touching the diaphragm thereof. The tubular part, 13, of the said amplifier 1, terminates in a trumpet, 14, and the amplifier 1, is by appropriate conformation, so shaped that the trumpet, 14, thereof will be in juxtaposition to the ear of the speaker, when in the act of talking into the transmitter, 15 of the telephone.

The bracket attached adjacent to the switch-hook of the telephone is held rigid, in the case of a desk-phone, by means of the two screws, 16 and 17 which unite the two parts of the collar 4 which is substantially a divided clamp. The cam 5, is held in place by the pin 8 which passes through the arms 18 and 19, forming extensions to the two parts of the collar 4. The flat strips 6 and 7 are parts of the collar 4, extending downward. The holder 9, for the receiver is a resilient hook of two equal parts held rigid to the flat

strips 6 and 7 by the screws 20, 21, 22, and 23, and extends substantially at right-angles to the flat strips 6 and 7 toward the lower end of the receiver 3 when the receiver is on 5 its rack, and is adapted to engage the receiver and hold it in a vertical position.

When it is desired to make a telephonic connection, the pin 8 is turned whereby the cam 5, lifts the switch-hook into the position 10 it would occupy if the receiver were removed from its rack; and when it is desired to break the telephonic connection, the pin 8 is turned in the opposite direction, whereby the flattened part of the cam is upward, thus 15 allowing the switch-hook to fall into the position it normally occupies when supporting the receiver.

Fig. 6 shows a modification in the use of the sound-amplifier when it is desirable to 20 attach it to the receiver of a telephone without inverting the receiver on its rack; the advantage being only more nearly perfect stability and more pleasing appearance. It will be seen therefore, that my attachments 25 can be readily affixed to any telephone and that they are adapted for use as permanent attachments.

The advantages of my device are also obvious. The peculiar conformation of the 30 sound-amplifier enhances the acoustic effects of the telephone receiver so that actual contact of the ear to the trumpet-end of the amplifier is not necessary, wherefore the speaker need not run the risk of infection— 35 thus providing a sanitary precaution especially desirable in a telephone in more or less public use, in which the ordinary receiver is constantly exposed to disease germs, etc.

40 The chief advantage and purpose of my device is, however, in the saving of time for the person using the telephone equipped with my attachments. In order to make the connection, it is necessary only to rotate the 45 cam 5 by turning the pin 8. Instantly the switch-hook is raised and the connection made, allowing the person desiring to carry on a telephonic conversation the free use of both hands during the entire conversation, 50 while waiting for the person at the other end of the line to come to his telephone, and during all interruptions in the conversation. At the conclusion of the conversation the connection is as quickly and easily broken by 55 rotating the cam 5, in the opposite direction, whereby the switch-hook of the phone is again lowered.

While I have illustrated and described only one specific embodiment of my invention, having especially in mind the type of telephone called "desk-phone," I am aware that it is susceptible of modifications and of adaptability to the ordinary wall telephone, the pay-station telephone, the telephone 60 exchange systems and every other kind of tele-

phone; and I do not desire to be limited to the precise form shown.

Having thus fully described my invention, I claim and desire to protect by Letters Patent of the United States:

1. The combination with a telephone, of a bracket attached thereto adjacent to the switch-hook of the telephone, of a receiver supported on the switch-hook and means carried by the bracket for holding the telephone-receiver. 7

2. The combination with a telephone of a bracket attached thereto adjacent to the switch-hook of the telephone, of a receiver supported on the switch-hook and means carried by the said bracket for operating the switch-hook and holding the same raised in operating position. 8

3. The combination with a telephone of a bracket attached thereto adjacent to the switch-hook of the telephone, of a receiver supported on the switch-hook, means carried by the bracket for holding the telephone receiver and means carried by the bracket for operating the switch-hook and holding the same raised in operating position while the telephone is being used. 9

4. The combination with a telephone, of a bracket attached thereto adjacent to the switch-hook of the telephone, of a receiver supported on the switch-hook, of a sound amplifier rigidly attached to and carried by the receiver and means carried by the bracket for holding the telephone receiver in position. 9½

5. The combination with a telephone of a bracket attached thereto adjacent to the switch-hook of the telephone, of a receiver supported on the switch-hook, of a sound amplifier rigidly attached to and supported by the receiver, means carried by the bracket for holding the receiver in position and means carried by the bracket for operating the switch-hook and holding the same in a raised position while the telephone is in use. 10

6. The combination, with a telephone, of a bracket removably attachable adjacent to the switch-hook of the telephone, a cam affixed to the said bracket and means for rotating the said cam in such manner as to make, sustain and break the telephonic connection. 11

7. The combination with a telephone, of a bracket removably attachable adjacent to the switch-hook of the telephone, a shaft affixed to the said bracket, journaled in bearings and equipped with a cam, means to rotate the said cam in such manner as to lift, keep raised and lower the switch-hook of the telephone and thereby to make, sustain and break telephonic connections, and of a holder for the telephone receiver affixed to the said bracket. 12½

8. A bracket removably attachable to a telephone adjacent to the switch-hook there- 13½

- of, the said bracket comprising a collar, a holder for the telephone receiver, a bar portion connecting the collar with the said holder and upright supports from the bar forming bearings for means for operating the switch-hook of the telephone; the said means comprising a cam equipped with a rotatable shaft terminating in a head or button.
9. A bracket, removably attachable to a telephone, comprising a collar, a holder for the telephone receiver, a bar portion connecting the collar with the said holder, upright supports from the said bar portion, a shaft journaled in bearings, a cam attachable to the said shaft and means carried by the said shaft for operating the said cam in such manner as to raise, keep raised and lower the switch-hook of the telephone.
10. The combination with a sound-amplifier, removably attachable to the telephone-receiver, of a bracket removably attachable to the telephone adjacent to the switch-hook thereof, and comprising a flattened disk in the nature of a cam, means to rotate the said disk to lift and lower the switch-hook of the telephone, and comprising a holder for a telephone-receiver, and means for holding the receiver in a vertical position, and means for holding the delivery end of the sound amplifier in such position as to bring the mouth of the said amplifier in juxtaposition to the ear of the speaker when in the act of normally talking into the transmitter of the telephone.
11. The combination with a telephone, of a sound amplifier removably attachable to the telephone-receiver, of a bracket removably attachable to the telephone adjacent to the switch-hook thereof and comprising a cam, means to rotate the said cam to lift, keep raised and lower the switch-hook of the telephone sufficiently to make, sustain and break telephonic connections, and comprising a holder for the telephone-receiver and means for holding the receiver in a vertical position, and means for holding the delivery end of the sound amplifier in such position as to bring the mouth of the said amplifier in juxtaposition to the ear of the speaker when in the act of talking into the transmitter of the telephone.
